UNITED STATES PATENT OFFICE

FRANK R. CHESTER, OF NEW YORK, N. Y., ASSIGNOR TO CHESTERFIELD CONTROL COMPANY, OF DOVER, DELAWARE, A CORPORATION OF DELAWARE

FIGHT GAME

Application filed March 5, 1928. Serial No. 259,165.

This invention relates to a structurally and functionally improved game and aims particularly to provide a mechanism whereby, in a miniature embodiment of a real game or contest, the movements of the players or contestants will appear extremely life-like and wherein the movements of real persons may be duplicated with fidelity.

It is an object of the invention to provide a device of this character, the parts of which will be relatively few in number and individually rugged and simple in construction, these parts being capable of ready assemblage to provide a game or machine operating over long periods of time with freedom from mechanical difficulty.

Another object is that of constructing a device of this type in which a safety provision will be afforded preventing destruction or mutilation of the game mechanism by persons who operate the same in an unintelligent manner.

While the features of the present invention may be employed to advantage in numerous different associations, they are primarily intended to be embodied in a fight game of the nature shown, for example, in my co-pending application, Serial No. 189,511, filed in the United States Patent Office May 7, 1927, and when so employed the present invention will serve to guard against breakage or damage to the parts and will serve to provide a fight or similar game in which the movements of the contestant figures will be extremely life-like in that the action of the figures will be retarded if the game mechanism is actuated by an operator with too great speed, so that no abnormal figure movements may result and, furthermore, figures and mechanism will not become damaged.

With these and further objects in mind reference is had to the attached sheet of drawings, wherein there is illustrated several practical embodiments of the invention, in which:

Figure 1 is a partly fragmentary, sectional side view of a game embodying one form of mechanism constructed in accordance with the present invention;

Fig. 2 is a fragmentary enlarged view of a detail thereof;

Fig. 3 is a transverse, sectional view taken through Fig. 2;

Fig. 4 is a sectional plan view of certain of the operating mechanism;

Fig. 5 is a fragmentary side elevation of a slightly different form of mechanism than that shown in Fig. 1, and

Fig. 6 is a partly fragmentary plan view of certain of the parts as shown in Fig. 1.

In these views the numeral 10 indicates a base which may form a part of, or be enclosed by a cabinet (not shown) and which, in any event, is preferably hollow to provide a space for the accommodation of mechanism hereinafter referred to. This base, or deck, in accordance with the preferred embodiment of the invention, serves as an apparent mounting for two opposed fighter figures and is formed with a slot 11 through which the figure-operating and mounting mechanism may extend. Also, in view of the embodiment which has been illustrated, the deck may support a barrier 12 simulating a boxing ring and beyond the side walls which support the deck pairs of handles 12 of any desirable type may extend for actuating the figure mechanism.

With reference to the figures: They are duplicates of each other and include, in each instance, a nether portion 13, a body 14, a head 15 and sectional arms 16. The body portion is axially rotatable with respect to the nether portion around a shaft 17 which mounts, at its upper end, a gear 18, the teeth of which mesh with a pair of gears 19 secured to shafts 20 having their outer ends extending beyond the body and at which point they are attached to the upper sections of the arms 16.

A gear 21 is secured to the body portion and meshes with the teeth of gear 22 supported by a crank shaft 23, which may be actuated by a pitman 24 having its lower end attached to the crank portion (not shown) of a crank shaft 25. As a consequence, when this latter shaft is oscillated the shaft 23 will be likewise moved to shift the gear 21 and consequently the body portion with respect to the nether portion of the figure. As a result of

this movement, the shafts 20 will be rotated and the arms will be projected to a striking position. The head is pivotally mounted as at 26 upon the body portion and has an extension which is link-connected as at 27 to a trip rod or plate 28, the latter forming one arm of a bell crank member, the second arm of which is provided by the solar plexus portion 29 of the body, this bell crank member being pivotally supported as at 30 by the body. The bar or plate 28 engages one end of a spring-pressed rod 31, which terminates in a forked latch portion 32 normally straddling a shaft 33. This shaft is supported by a bracket 34 which also mounts an arcuate rack 35 normally retained in upright position by a weighted extension 36 and the teeth of which mesh with a gear portion 37 extending from or forming an integral part of the nether portion of the figure. Thus, the figure is normally held upright, but if the head or the solar plexus portion of the body is rocked around its pivots, the rod 31 will be retracted and the parts are preferably so proportioned and arranged that the figure will topple rearwardly in the manner indicated in Figure 1.

The foregoing mechanism has been shown and described in greater detail in the copending application afore referred to and except in the combination hereinafter stated, forms no part of the present invention. Likewise, in said application a convenient form of mechanism has been illustrated which will re-establish the position of the figure upon the same assuming a recumbent plane.

The crank portion of the shaft 25 is actuated, for example, by means of the mechanism also shown in the aforementioned application and which embraces a parallel link movement 38, the upper member of which is slotted to accommodate the crank end 39 of such shaft irrespective of whether the figure be projected or retracted along the base 40. This parallel link is modified, however, in that the end members thereof, which are supported by shafts 40, are preferably extended below these shafts and have their lower ends connected to each other by a link 41. It has been found that by such a construction the parts work with greater accuracy and the danger of the mechanism becoming disarranged is reduced materially. The bracket 34 is supported at the inner end of a carriage 42 which has a rack portion 43, the teeth of which are engaged by a gear 44 supported upon a shaft 45, this shaft mounting one of the handles 12 so that the entire carriage and consequently the figure, may be moved along the deck. As indicated in Figure 1, the second knob or handle for actuating one figure may be connected directly to one of the shafts 40. In such event this shaft is split, as has been indicated in Figure 3 and in its forward end is formed with a slot through which

a spring 46 extends, the ends of this spring projecting through openings in a drum 47 and being conveniently bent as at 48 so that they may not be accidentally withdrawn from the openings of the drum. The drum 70 has a hub 49 which is secured to the rearward portion of the shaft 40 and it is this portion which may have one of the end members of the parallel link movement secured to it. Thus, it will be obvious that no matter how rapidly the handle is turned, a yielding connection will be provided between this handle and the parallel link movement, so that the parts may not be actuated with too great rapidity. Additionally, it will be patent that if both figures are in a position immediately adjacent each other, that by this construction it will be impossible to force the hand portions of the arms against the body of the opponent figure with such power that the mechanism would be damaged.

If it is found, in certain instances, that the speed with which the parts may be operated is still too great to simulate a normal contest, the structure proposed in Figure 4 may be resorted to, in which the shaft 50 mounts the handle and is split and carries a yielding-connected element for its parts, as has been indicated at 51 and which connection may be in the nature of that shown and described in Figures 2 and 3. However, in this instance the hub of the drum mounts a gear 52, the teeth of which mesh with a larger gear 53 which, by means of a crank 54 and pitman 55 connects with one of the end members of the parallel link movement, it being thus obvious that a retard action is assured.

If the yielding connection afore suggested is not desired a connection may be employed of the nature shown in Figure 5, in which the shaft 56 corresponds to either the shafts 50 or 54 aforesaid and mounts a crank 57 which moves a rod 58 fixedly carrying one end of a compression spring 59, the opposite end of which is connected to a block 60 mounted slidably upon the rod 58 and secured to one of the end members of the parallel link movement, it being obvious that by this construction the desired results are again achieved.

As has been shown in Figure 6, the shaft 45 may likewise be split and be provided with a yielding connection indicated at 61, this connection corresponding to the forms shown in Figs. 2 and 3 and obviously serving to prevent too rapid a projection and retraction of the figure.

It will here be obvious, however, that if desired this shaft may additionally or otherwise have its transmitting motions modified.

Finally, reference again being had to Figure 1, it will be observed that a bellows member 62 may be connected to the end member of the link motion and act to retard the movements of the parts, it being understood that

this member is preferably of conventional construction and has a bleeder opening which may be valve controlled as at 63, so that the speed with which the parts may be actuated 5 irrespective of whether a reduction drive is employed or not, may be accurately gauged and regulated. It is obvious, however, that this retarding member may be provided in other positions within the mechanism and 10 connected to desirable elements thereof in order to effect the results desired.

From the foregoing it will be appreciated that an extremely life-like operation of the game may be achieved irrespective of whether the operator actuates the game mechanism 15 in an intelligent manner or not. Also, it will be obvious that it will be impossible to cause the game mechanism to be actuated in such a manner that the parts thereof will be damaged.

Thus, among others, the several objects specifically aforementioned are achieved. It is intended, however, that numerous changes 25 in construction and re-arrangement of the parts might be resorted to without departing from the spirit of the invention as defined by the claims.

Having described my invention what I claim as new and desire to secure by Letters 30 Patent is:—

1. A game including a figure, movable limb portions forming a part thereof, a pair of operating means connected to said figure, one for shifting the same back and forth and the 35 other for actuating said limb portions and resilient connections interposed in both said operating means.

2. A game including a figure, movable limb portions forming a part thereof, a pair of operating means connected to said figure, one for shifting the same back and forth and the other for actuating said limb portions, resilient connections interposed in both said 45 operating means and means associated with one of said operating means for retarding the actuation thereof.

3. A game including a figure, movable limb portions forming a part thereof, a pair of operating means connected to said figure, one for shifting the same back and forth and the other for actuating said limb portions, resilient connections interposed in both said operating means and means associated with said 55 limb operating means for positively retarding the actions thereof.

4. A game including a shiftable figure, movable limb portions forming a part of said figure, operating means for said limb portions, a parallel link movement embracing 60 four pivotally connected elements forming a part of said operating means and means extending between said link movement and figure for transmitting the movements of the former to the latter.

5. A game including, in combination, a

pair of figures, striking portions forming a part of each of said figures, means for actuating said figures to cause the striking portions of each figure to be impelled towards the other figure, operating means for said actuating means and means providing a yielding connection for limiting the amount of force with which the striking portion of one figure may engage another figure and irrespective of the force with which said operating means is actuated.

6. A game including, in combination, a pair of figures, striking portions forming a part of each of said figures, means for actuating said figures to cause the striking portions of each figure to be impelled towards the other figure, operating means for said actuating means and retarding means associated with said operating means for limiting the speed with which the striking portions of the figures may be impelled.

7. A game including a pair of figures, striking portions forming a part of said figures and movable with respect thereto, means for shifting said figures towards and away from each other, actuating means for said striking portions, operating means for said actuating means and a resilient connection between said operating and actuating means and independent of said shifting means to limit the force with which the striking portion of one figure may engage the opposing figure.

8. A game including a pair of figures, striking portions forming a part of said figures and movable with respect thereto, means for shifting said figures towards and away from each other, and means independent of said striking portions and connected to said figure-shifting means to automatically limit the force with which one figure may be moved towards and away from the opposing figure.

9. A game including a pair of figures, striking portions forming a part of each of said figures, means for mounting said figures to be shiftable towards and away from each other, operating means for said shifting means, further operating means for said striking portions and independent resilient connections forming a part of both of said operating means to limit the force with which said striking portions may be projected and the force with which said figures may be shifted.

10. A game including a pair of figures, striking portions forming a part of each of said figures, means for mounting said figures to be shiftable towards and away from each other, operating means for said shifting means, further operating means for said striking portions, resilient connections forming a part of both of said operating means to limit the force with which said striking portions may be projected and the force with which said figures may be shifted, and means for re-

tarding the speed of projection of said striking portions.

11. A game including a parallel link movement embracing four pivotally connected elements, a figure including a striking portion, actuating means extending from said portion and movable longitudinally of and connected to one of said elements, means for shifting said figure to have the actuating means thereof traverse said element and means for operating said parallel link movement.

12. A game including a parallel link movement embracing four pivotally connected elements, a figure including a striking portion, actuating means extending from said portion and movable longitudinally of and connected to one of said elements, means for shifting said figure to have the actuating means thereof traverse said element, means for operating said parallel link movement, and means connected to said link movement for retarding the operations thereof.

13. A game including a figure, a support, means for advancing and retracting the figure over said support, striking portions forming a part of said figure, manually operated means for causing a functioning of said advancing and retracting means, and independent manual means for causing an operation of said striking means, and said manually operated means including reduction gearing for reducing the speed with which said figure may be advanced and retracted and the striking portions thereof may be manipulated.

14. A game including a figure, a support, means for advancing and retracting the figure over said support, striking portions forming a part of said figure, manually operated means for causing a functioning of said advancing and retracting means and an operation of said striking portions, and a bellows element associated with the mechanism of said game for limiting the speed with which said figure may be moved with respect to its support irrespective of the speed of operation of said manually operated means.

15. A game including a figure, a support, means for advancing and retracting the figure over said support, striking portions forming a part of said figure, manually operated means for causing a functioning of said advancing and retracting means and an independent operation of said striking portions, and resilient connections interposed between said manually operated means and the means for moving the figure and portions of the same with respect to said support whereby to limit the force of movement of said figure and portions.

In testimony whereof I affix my signature.
FRANK R. CHESTER.
